REFRIGERATING UNIT

Richard W. Kritzer, Chicago, Ill., assignor to
Peerless Ice Machine Company, Chicago, Ill.

Application March 25, 1929, Serial No. 349,840

18 Claims. (CL. 62—126)

My invention relates to improvements in refrigerating units, and it consists in the combinations, constructions, and arrangements herein described and claimed.

- 5 An object of my invention is to provide a refrigerating unit having an outer and an inner shell formed from a single sheet of material to provide a refrigerant liquid space around the unit.
- 10 A further object is to provide a refrigerating unit of a type which will necessitate a minimum amount of refrigerant liquid.

15 A further object is to provide a device of the type described in which the float valve mechanism may be actuated by a minimum amount of refrigerant liquid.

20 Other objects and advantages will appear in the following specification, and the novel features of the invention will be particularly pointed out in the appended claims.

25 My invention is illustrated in the accompanying drawing, forming part of this application, in which

Figure 1 is a longitudinal sectional view of my device,

Figure 2 is a front elevation, partly in section, of the device shown in Figure 1, and

Figure 3 is a diagrammatic view of a refrigerating system embodying my invention.

30 In carrying out my invention, I provide a refrigerating unit 1 comprising an outer shell 2 and an inner shell 3 formed from a single piece of material. The material is doubled as at 4 and the outer shell 2 is spaced away from the inner shell 3 as shown in Figures 1 and 2. The inner shell 3 is depressed as at 5 for forming a compartment within which a float 6 is disposed. As will be seen by referring to Figures 1 and 2, the depressed portion 5 conforms substantially to the 40 contour of the float 6.

The ends 7 and 8 of the inner and outer shells 2 and 3, respectively, are welded together as at 9. A cover 10 is secured to one end of the unit 1 by means of bolts 11 which are welded to the outer and inner shells as shown in Figure 1. The cover 10 is provided with a threaded opening 12 within which a feed pipe 13 is disposed. The cover is also provided with a boss 14 having an opening 15 communicating with the opening 12.

45 The float 6 is suspended from an arm 16 pivotally connected at 17 to a pair of projecting lugs 18 formed integral with the cover 10. The arm 16 is provided with a valve 19 which is arranged for closing the passageway 15, see Figure 1.

55 In referring to Figure 2, it will be seen that

a freezing chamber 20 is provided within which a freezing pan 21 may be disposed. The bolts 11 are welded to the outer and inner shells 2 and 3, respectively, as shown at 22 in Figure 1. The cover 10 is provided with an opening 23 within which a vapor pipe 24 is secured.

From the foregoing description of the various parts of the device, the operation thereof may be readily understood. In Figure 3 I have indicated diagrammatically an installation embodying my invention. The refrigerating unit 1 is disposed within a refrigerator 25. The vapor pipe 24 is connected with a main vapor line 26. The vapor line 26 is operatively connected with a compressor 27 which is operated by means of a motor 28 connected with a source of current through conductors 29 and 30.

The compressor 27 is connected with a condenser 31 by means of a pipe 32. The feed pipe 13 is operatively connected with a main feed pipe 33 which is operatively connected with the condenser 31.

In operation, when the compressor 27 is working, the refrigerant vapor will be forced into the condenser, where it is cooled and liquefied. The liquid within the condenser is forced into the feed line 33 and through the pipe 13. The refrigerant liquid which passes through the pipe 13 is forced through the passageway 15 and flows into the depression or recess 5. The refrigerant liquid will flow over the formation 34 and pass into the space between the outer and inner shells. When the liquid within the refrigerating unit has reached an approximate level indicated by the line 35, the float 6 will be lifted sufficiently far for moving the valve 19 into a closing position with respect to the passageway 15.

It will thus be seen that I have provided a refrigerating unit in which a minimum amount of refrigerant liquid is required. In addition to this the construction is such that the float 6 is actuated by a relatively small amount of refrigerant liquid. After a certain amount of liquid has been vaporized, the liquid level within the depression 5, which may be termed the float chamber, is such that the float will be lowered for moving the valve 19 out of engagement with the passageway 15, whereby additional refrigerant liquid is permitted to enter the unit. The vaporized liquid is drawn from the refrigerating unit through the pipe 24. In forming the unit, I preferably employ a tubular sheet of material. It is not of course necessary to employ the tubular sheet since the unit may be made from a sheet of material and welded together at the connecting line.

I claim:

1. A refrigerating unit comprising two shells one inside the other with a space between them, said shells being formed of a single piece of metal, which piece also forms a connecting wall between them at one end, to close said space at that end, said inner shell being cupped at one end to define a float-receiving chamber. 5
2. A refrigerating unit comprising two shells one inside the other with a space between them, said shells being formed of a single piece of metal which piece also forms a connecting wall between them at one end, to close said space at one end, said inner shell being cupped at one end to define a float-receiving chamber. 10
- 15 3. A refrigerating unit comprising two shells one inside the other with a space between them, said shells being formed of a single piece of metal which piece also forms a connecting wall between them at one end, to close said space at one end, said inner shell being cupped at one end to define a float-receiving chamber, said float-receiving chamber being located near the top of the unit, the metal of said inner shell at one side of said chamber being bent to define an overflow lip. 15
- 20 4. A refrigerating unit comprising two shells one inside the other with a space between them, said shells being formed of a single piece of metal which piece also forms a connecting wall between them at one end, to close said space at one end, said inner shell being cupped inwardly at one end to define a float-receiving chamber, said float-receiving chamber being located near the top of the unit, the metal of said inner shell at both sides of said chamber bent inwardly and 25 downwardly to define an overflow lip. 30
- 35 5. A refrigerating unit comprising two shells one inside the other with a space between them, said shells being formed of a single piece of metal which piece also forms the connecting wall between them at one end, to close said space at one end, said inner shell being cupped inwardly at one end to define a float-receiving chamber, and a welded joint closing the narrow portion 35 of the open end of said space. 40
- 45 6. A refrigerating unit comprising two shells one inside the other with a space between them, said shells being formed of a single piece of metal which piece also forms a connection between them at one end, to close said space at that end, said inner shell being cupped inwardly at one end to define a float-receiving chamber, a welded joint closing the narrow portion of the open end of said space, and a cover plate for closing the 45 open end of said float chamber. 50
- 55 7. A refrigerating unit comprising two shells, one inside the other with an annular space between them, said shells being formed of a single piece of metal which piece also forms a connecting wall between them at one end, to close said annular space at one end, said inner shell being cupped inwardly at one end to define a float-receiving chamber, a cover plate for closing the open end of said chamber, and float and valve control means assembled as a unit with said 55 cover plate. 60
- 65 8. A refrigerating unit comprising two shells one inside the other with a space between them, said shells being formed of a single piece of metal which piece also forms a connecting wall between them at one end, to close said space at one end, said inner shell being cupped inwardly at one end to define a float receiving chamber, a cover plate closing the open end of said chamber, said cover plate carrying inlet and outlet 70 connections and float control means for one of said connections. 75
9. A refrigerating unit comprising two shells one inside the other with a space between them, said shells being formed of a single piece of metal which piece also forms a connecting wall between them at one end, to close the space at one end, said inner shell being cupped inwardly at one end to define a float receiving chamber, and a float in said chamber closely conforming to the shape of said chamber below the liquid level. 80
10. A refrigerating unit comprising a tubular member bent to position substantially half of the member inside the remaining half in spaced-apart relation therewith, a portion of one of the halves being bent away from the other half to define a float-receiving chamber, and means for closing the space between the halves around their edges at one end of the unit. 90
11. A refrigerating unit comprising a tubular member bent to position a portion of the member inside the remaining portion in spaced-apart relation therewith, the space between the inner portion and the outer portion being adapted to receive a refrigerant, the space within the inner portion defining a freezing chamber, the ends of said tubular members terminating in a common plane, one portion being bent away from the remaining portion to define a float-receiving chamber, and means for closing the space between the inner and outer portions around their edges at one end of the unit. 100
12. A refrigerating unit comprising an inner shell and an outer shell formed of one piece of material with a space between them and shaped to provide a freezing chamber, said piece of material forming a wall between the shells at one end, the space between the shells at the opposite end being welded together partly around the unit, a cover plate for closing the remaining space between the two shells at said opposite end, and bolt means welded to said shells and arranged for fastening the cover plate in position. 110
13. In a refrigerating unit, a single piece of sheet metal bent to provide a space for liquid refrigerant, a space for refrigerant vapor, a float chamber, and a freezing chamber, said metal having a main bend around the periphery of one end of the unit in a plane normal to the axis of said freezing chamber. 120
14. In a cooling unit, a single piece of sheet metal shaped to provide space for refrigerant material, a float chamber, and a freezing chamber, said metal having a main bend around the periphery of one end of the unit in a plane normal to the axis of said freezing chamber. 130
15. In a cooling unit, a single piece of sheet metal shaped to provide space for refrigerant material, a float chamber, and a freezing chamber, said freezing chamber having open ends, and said space extending peripherally entirely around said freezing chamber. 135
16. In a cooling unit, a single piece of sheet metal shaped to provide space for refrigerant material, a float chamber, and a freezing chamber, said space and float chamber each having one end axially open and accessible, but being otherwise completely defined and enclosed by said single piece of metal. 140
17. An annular refrigerating unit with an opening extending axially through the unit to define a freezing chamber, said unit comprising 150

two shells, one inside the other with a space between them, both shells encircling said freezing chamber, said shells being formed of a single piece of metal, which piece also forms an annular connecting wall between the shells at one end, to close the space between the shells at that end, and a closure for the other end of the space between the shells.

18. An annular refrigerating unit with an opening extending axially through the unit to define a freezing chamber, said unit comprising two shells, one inside the other with a space be-

tween them, both shells encircling said freezing chamber, said shells being formed of a single piece of metal, which piece also forms an annular connecting wall between the shells at one end, to close the space between the shells at that end, and a closure for the other end of the space between the shells, a portion of said shells around said chamber being more closely spaced, and an upper portion being more widely spaced, said widely spaced portion defining a chamber for housing control mechanism.
